REISSUED

UNITED STATES PATENT OFFICE

ROBERT K. WINNING, OF WAUWATOSA, WISCONSIN, ASSIGNOR, BY MESNE ASSIGNMENTS, TO THE DUDLEY LOCK CORPORATION, OF CHICAGO, ILLINOIS, A CORPORATION OF ILLINOIS

PERMUTATION LOCK

Application filed September 22, 1930. Serial No. 483,481.

This invention relates to improvements in permutation locks.

It is the primary object of the invention to provide a novel and improved and simple construction wherein pressure of the shackle may be used not only to push the bolt aside when the device is unlocked but may subsequently be used to re-engage the bolt when it is desired to cause the device to lock.

10 I am aware that attempts have previously been made to produce an arrangement for utilizing pressure of the shackle to engage the bolt therewith in a lock of this general type. It is my present specific purpose to 15 make a relatively simple device in which the parts will be rugged and their action certain to the end that difficulties heretofore encountered may be eliminated.

In the drawings:

20 Figure 1 is a front elevation of a lock case from which the permutation mechanism has been removed to expose in the bottom of the case the particular parts having principally to do with the present invention.

25 Figure 2 is a view showing the same parts with the locking disk of the permutation mechanism superimposed thereon.

Figure 3 shows the parts as they appear when the shackle is pressed to open the lock.

30 Figure 4 shows the final position of the parts as the shackle is withdrawn.

Figure 5 shows the parts as they appear during a subsequent downward movement of the shackle.

35 Figure 6 shows the parts in the position which they occupy as the shackle reaches its downwardmost position.

Figure 7 is a view of the complete lock in transverse cross section on the line shown at 40 7-7 in Fig. 1.

Like parts are identified by the same reference character throughout the several views.

The lock is of the general type illustrated in the United States Letters Patent No. 1,736,45 183 dated November 19, 1929 in which a lock case 8 is provided internally with a mounting plate 9 having an upturned ear 10 for guiding shackle 11. A central post is provided at 12 upon which permutation disks 13 and 14 are 50 guided, the disk 15 being connected with the

hub portion 16 of a knob 17 journaled in the cover 18 for the case.

The mounting plate 9 also carries posts 19 for the spacer members 20 which are formed as illustrated in Figure 5 of said patent and are interposed between successive disks of the permutation device. The final disk 13 of the series is shown in Figures 2 to 7 inclusive and is provided at 23 with a notch into which the flange keeper portion 24 of the oscillatory bolt 25 is receivable when said notch is aligned with the corresponding notches of the other disks and in registry with flange 24.

55 The free arm of the shackle 11 is also notched at 26, its faces at opposite sides of the notch being inclined from its inside surface toward its end. The end of the free arm of the shackle 11 is correspondingly beveled at 27. The structure thus far described is 60 illustrated in the above identified patent. I shall now refer to features which have been added for the purpose of the present invention.

65 Beneath disk 13 and separated therefrom by a special spacer 28 is a pawl carrying lever 30 of the peculiar form clearly shown in Fig. 1. At one end it is provided with an open bearing 31 while at the other it carries pivotally a pawl 32 of which the free or active 70 end carries a lug 33 and torsion spring 34 tends to throw the free end of the pawl toward the post 12 upon which lever 30 is fulcrumed.

75 Overlying the bolt 25 and the bearing end of the pawl carrying lever 30 is an actuating lever 35 carrying a pin 36 engaged in the open bearing 31 of lever 30. Lever 35 has an upturned flange at 37 notched to serve as an anchorage for the torsion spring 38 as best 80 shown in Fig. 7 and adapted also to provide a bearing surface for the beveled end 27 of the shackle.

85 With the parts shown in Fig. 1, the permutation disks are manipulated until their respective notches register with the keeper flange 24 of bolt 25 as illustrated by the position of disk 13 in Fig. 2. The permutation mechanism now being in a position to permit 90 the opening of the lock, the operator will 95 100

press on the bight of the shackle to move the shackle against the spring 40 toward the position illustrated in Fig. 3. The beveled surface 27 of the shackle will ride upon the inclined margin 41 of the bolt 25 to oscillate the bolt counterclockwise about its fulcrum pin 42. This motion is permitted by entry of the flange 24 into notch 23. At the same time the beveled surface 27 of the shackle engages flange 37 of the actuating lever 35 to oscillate this lever also in a counterclockwise direction about its fulcrum pin 44.

10 The counterclockwise oscillation of lever 35 produces clockwise oscillation of lever 30. While the movement of these parts performs no function at this particular time due to the fact that the pawl lug 33 is not engaged in any of the peripheral notches 45 of disk 13, the movement has been described for the reason that it is necessary in this device to provide for such movement and to make provision also for guarding against displacement of disk 13 as the result of such movement.

15 With the parts in the position illustrated in Fig. 3 the shackle may now be withdrawn. The distorted spring 40 will assist in its initial outward movement toward the position in which the shackle is illustrated in Fig. 4. In the course of such outward movement the 20 end portion of the shackle beyond notch 26 will engage the inclined end face of the keeper flange 24 to force the keeper flange to its ultimate position in the notch 23 of permutation disk 13. The withdrawal of the shackle allows 25 spring 38 to force lever 35 in a clockwise direction as viewed in Figure 4 beyond the original position in which such lever was held by the shackle in the Fig. 2 disposition of the parts. Obviously the movement of lever 35 is transmitted through pin 36 to lever 30 and as a result of the new extreme position of lever 30 the lug 33 of the ratchet dog 32 passes about the periphery of permutation disk 13 to a point where it will be sure of engagement 40 with one of the notches 45 during its return movement.

45 The ultimate position of the levers is defined by the engagement of notched portion 46 of lever 35 with the keeper flange 24. It is particularly to be noted that in this position of the parts as shown in Fig. 4 the lever 35 acts as a compression member to restrain keeper 24 from any movement out of engagement with notch 23 of the permutation disk. 50 The important result of this interaction of the parts is to prevent any displacement either of the keeper or the disk while the hasp is withdrawn. There is sufficient lost motion between the position of lug 33 in Fig. 4 and the shoulder of the nearest adjacent notch 45 so that the portion 46 of lever 35 which performs the obstructing function just described will move out of the way as shown in Fig. 5 before lug 33 is fully engaged with notch 45 55 and the rotation of disk 13 is commenced.

When it is desired to lock the shackle, it is subjected to pressure tending to force its shorter end into the lock casing, which it enters as shown in Fig. 5. Its initial engagement with the bearing flange 37 of lever 35 70 will cause a counterclockwise movement of lever 35 and a corresponding clockwise movement of lever 30 which will have the effect of engaging lug 33 snugly in the adjacent notch 45 and removing portion 46 of lever 35 from 75 the path of the keeper as aforesaid.

80 The succeeding movement of the shackle 11 under continued pressure exerted by the operator will cause a continued movement of levers 35 and 30 in the respective directions just described, and the engagement of lug 33 with permutation disk 13 will produce clockwise rotation of such disk to the position in which it is illustrated in Fig. 6. It will be noted that the direction of thrust of the left-hand edge of the notch 23, of said disk upon the keeper flange 24 will be such as to tend to oscillate the keeper flange and its associated bolt lever 25 in a clockwise direction about the fulcrum 42 whereby to re-engage 90 the bolt in notch 26 of the shackle.

95 The movement described will continue until the notch 23 in permutation disk 13 has passed entirely out of registry with keeper flange 24 as shown in Fig. 6. In this position of the parts, spring 40 engaging the longer end of the shackle will be somewhat distorted and consequently, upon release of the shackle by the operator, the spring 40 will force the shackle back to the position in which it is illustrated in Figs. 1 and 2, thereby engaging the keeper flange 24 to its full depth in notch 26 and allowing levers 35 and 30 to return to a position in which the lug 33 is disengaged 100 from permutation disk 13.

105 It is particularly to be noted that the normal locked position of the parts is such that the levers 35 and 30 are both intermediate the ends of their paths of movement. It is this fact, taken with the multiplication of movement afforded by the use of the levers 35 and 30, which ensures the accurate and positive interaction of the parts. It is not until the shackle is unlocked and partially withdrawn from the lock casing that lug 33 engages permutation disk 13 and the relatively large angular rotation of such disk produced by a relatively short movement of the shackle after it re-enters the casing positively moves the disk out of registry with the keeper.

110 Another important means of securing accuracy is the use of a pawl carrying lever 30 which is fulcrumed directly on post 12 and the pawl of which is engaged directly with the periphery of disk 13.

115 To prevent the permutation disk from undesired rotative displacement and particularly to protect disk 13 from displacement such as might otherwise be occasioned by the frictional engagement of lug 33 with its pe- 120

riphery, I prefer to employ a small compression spring at 48 on post 12 which maintains intimate contact between the permutation disks and the several spacers 20 and 28. The resulting action is equivalent to that of a friction clutch tending to hold each disk stationary until it is positively displaced.

I claim:

1. A permutation lock provided with means for utilizing the entering movement of its shackle for engaging a keeper therewith, said means comprising the combination with a permutation disk provided with means for interacting with a keeper, of a pair of levers in motion transmitting connection, one of said levers being pivoted co-axially with said disk and provided with means engageable with said disk for the rotation thereof and normally disengaged therefrom, the other of 20 said levers being positioned for operation by a portion of said shackle.

2. In a permutation lock, the combination with a notched shackle, a notched permutation disk, and a keeper alternatively engageable therewith, of a stop member movable to a position of engagement with the keeper when the latter is engaged in the notch of said disk and adapted in said position to restrain said keeper from disengagement, a spring 30 pressing said stop member toward said position, and means on said stop member with which said shackle is normally engageable when locked to maintain said stop member in a retracted position such as to permit free 35 movement of said keeper.

3. In a permutation lock, the combination with a notched shackle, a notched permutation disk, and a keeper alternatively engageable therewith, of a stop member movable to 40 a position of engagement with the keeper when the latter is engaged in the notch of said disk and adapted in said position to restrain said keeper from disengagement, a spring pressing said stop member toward said position, and means on said stop member with which said shackle is normally engageable 45 when locked to maintain said stop member in a retracted position such as to permit free movement of said keeper, together with lost 50 motion connections from said stop member to said disk for the rotation of said disk in a direction to disengage the keeper therefrom following the movement of said stop member to its retracted position.

55 4. In a permutation lock, the combination with rotatable means provided with peripheral notches, of a bolt member having a keeper portion movable into cooperative engagement with a notch of said means, and 60 connections for the rotation of said means in a direction to cause the wall of said notch to act cam-wise on the keeper portion and disengage it from said notch, said connections comprising a dog carrying lever having a dog 65 engageable with said means, and a second

lever in pivotal connection with said dog carrying lever, each of said levers having its motion receiving portion closer to its fulcrum than its motion delivering portion whereby to multiply the motion transmitted to said means.

5. In a permutation lock the combination with notched rotatable means and a keeper having a portion engageable in a notch of said means, of connections for the rotation of said means in a direction to cause a wall of said notch to act cam-wise on said keeper portion for shifting it out of said notch, said connections comprising a pawl carrier fulcrumed co-axially with said means and a 70 pawl engageable with said means, a lever in pivotal connection with said pawl carrier at a radius less than that of said means, and a shackle with which said keeper is engageable upon its disengagement from said means, said shackle being movable in a path whereby it is engageable with said lever closely adjacent its fulcrum for oscillation of said lever in a direction to rotate said means through said carrier and pawl.

6. In a permutation lock, the combination with a shackle, a keeper, and a permutation disk having its periphery provided with a plurality of notches, of motion transmitting connections acting directly upon said notched periphery of the disk for rotating it in a direction to disengage the keeper therefrom, and including a member disposed in the path of movement of a portion of the shackle to receive motion from it.

7. In a permutation lock, the combination with a notched shackle, a permutation disk having its periphery provided with a plurality of notches, and a keeper alternatively engageable with a notch of the permutation disk or shackle; of a ratchet pawl positioned to interact directly with the notches of the disk, and motion-multiplying connections for the actuation of said pawl, including a part disposed in the path of movement of a portion of the shackle.

8. In a permutation lock, the combination with a locking element, a keeper co-operatively engaged therewith, of means for utilizing the movement of said locking element for locking the lock, said means comprising a permutation disk in the lock for controlling the movement of the keeper and having its periphery provided with a plurality of notches, a ratchet pawl engageable with said notched periphery of the disk, and motion-multiplying connections operatively connected with the ratchet pawl and including a member disposed in the path of movement of a portion of said locking element, whereby actuation of said connections causes said ratchet pawl to rotate said disk and thereby shift the keeper into operative engagement with the locking element.
